F. W. SMITH

COMBINED SASH HOLDER AND WINDOW RELEASE

Filed August 18, 1925

FIG. 3.

FIG. 4.

Inventor

F. W. Smith

UNITED STATES PATENT OFFICE.

FRIEND W. SMITH, OF BRIDGEPORT, CONNECTICUT, ASSIGNOR TO THE NATIONAL LOCK WASHER COMPANY, OF NEWARK, NEW JERSEY, A CORPORATION OF NEW JERSEY.

COMBINED SASH HOLDER AND WINDOW RELEASE.

Application filed August 18, 1925. Serial No. 50,993.

This invention relates to sash holders, but more particularly has reference to devices of this description such as are commonly used on railroad car windows and are 5 equipped with a vertically guided plunger pin, which, when the sash holder lever is raised to release the window from side racks in the casing, is driven downwardly against the sill of the window with sufficient force 10 to release the latter if it be stuck.

Constructions of this sort are not new as is evidenced by Letters Patent No. 1,547,775, issued July 28, 1925, to John L. Armstrong, but the object of the present invention is to 15 positively connect the plunger pin with an eccentric element that is carried by the sash holder lever, so that the upward and downward movements of the latter will cause said pin to be projected and retracted.

20 In the accompanying drawing

Figure 1 is an inside elevation showing the usual sash holder equipped with this invention, with the parts in their normal position.

25 Figure 2 is a similar view but showing the sash holder lever operated to withdraw the side catch of the sash, and the impinging bolt thrust downwardly.

Figure 3 is an inside view of the casing 30 with the parts removed, and

Figure 4 is a detail perspective of the sash holder lever.

Similar numerals of reference will be 35 used to denote like parts in the several figures of the drawing.

1 is the casing of the sash holder having formed therewith the usual dowels 2 to extend within the sash, 3 an L-shaped sash holder lever pivoted as usual around a post 40 4 extending rigidly from the casing, and 5 is the usual coil spring interposed between the inner lower end 6 of the member 3 and a side wall of the casing, whereby the action of the sash holder member is made resilient.

45 There is nothing whatever that is new with regard to the construction above described, since this is the ordinary sash holder commonly used on railroad car windows.

Integral with the inner portion of the 50 member 3 and extending laterally therefrom is a hollow hub 7 which surrounds the post 4 in pivotal relation thereto, the inside sur-

face of said hub being concentric with the axis of the pivot of said member 3, while the outside periphery of said hub is eccentric to 55 said axis and is denoted by the numeral 8.

Slidably housed within the bottom of the casing and within a boss 9 projecting therefrom is a plunger pin 10, which latter is capable of free movement beyond said boss to 60 contact the window sill which is denoted by the numeral 11.

The upper portion of this pin is enlarged and has therein a circular opening 12 through which the eccentric 8 extends snugly but is 65 free to revolve within this opening.

When the parts are in normal position with the sash closed, as shown at Figure 1, the uplift of the lever 3 will disengage the part 6 from the usual side rack in the casing, 70 and the continued uplift of this lever will cause the eccentric 8 to force the pin 10 downwardly against the sill 11 so as to release the lower rail of the sash if stuck to the sill, as is illustrated at Figure 2, and when the sash has been raised sufficiently 75 and the lever released, the spring 5 will cause the inner end 6 to engage the side rack in the casing to hold the sash open, and this swinging movement of the lever around the post 4 will cause the eccentric 8 to operate to 80 retract the pin to normal position, so that, when the sash is open, there will be no projection of the pin below the sash.

What is claimed is:—

A combined sash holder and window release, comprising a casing, a sash holder lever pivoted at its inner end within said casing and having a hub extending laterally from said end and forming a part of the pivotal portion, said hub having an eccentric periphery, and a vertically disposed plunger pin guided within the bottom of said casing and having in its upper end a circular opening which closely fits around said periphery, whereby the upward movement of said lever will cause said pin to be forced downward against the window sill and the upward movement will return said pin to its normal elevated position.

In testimony whereof I affix my signature hereto.

FRIEND W. SMITH.
